Howson and Howson

UNITED STATES PATENT OFFICE

HENRY JOHNSON, OF COVENTRY, ENGLAND, ASSIGNOR TO THE VISCOSE COMPANY, OF MARCUS HOOK, PENNSYLVANIA, A CORPORATION OF PENNSYLVANIA

SPOOL FOR YARNS OR THREADS

Application filed September 23, 1930. Serial No. 483,916.

My invention relates to the construction of spools which are designed for use in the manufacture of yarns and threads, natural or artificial, and the object of my invention is to provide a construction of spool which will not be liable to break the yarn or thread while it is being drawn off the spool in twisting, spinning, knitting or the like. This object I secure by making the spool in two parts each of which carries its own flange, one part being a tubular body upon which the thread or yarn is wound in the first instance and the other being a core with expansible frictional means to hold it in the tubular part when desired, but this core with its flange being removable and replaceable by a separate flanged piece when the yarn or thread is to be drawn off the spool.

In the accompanying drawing:

20 Fig. 1 is a longitudinal section through the tubular part of the spool, but with the expansible core in place;

Fig. 2 is a transverse section on the line 2—2, Fig. 1;

25 Fig. 3 is a side view of the expansible core removed;

Fig. 4 is a sectional view of a form of flange, to be substituted for the removed expansible core, in unwinding;

30 Fig. 5 is a sectional view of the wound spool, with the expansible core removed and replaced by a flanged piece, the position of the spool being here shown as upright, as it would be standing for drawing off the yarn or thread in a twisting machine or a knitting machine for example.

The part of the spool on which the thread or yarn is wound consists of a tubular part A, which conveniently may be of wood, and 40 having secured to one end as by screws, or other suitable means, a flange B, preferably of metal.

Combined with this tubular part is a frictional core C, preferably of metal and having secured to one end by any suitable means a flange C'. For lightness this core may be made of aluminum or other light metal in the form of a longitudinal central spindle c with spaced end and central flanges c', c² and 50 c³. There may be secured to the end flanges

a number of outwardly bowed longitudinal spring wires w, whose ends, one or both, are fitted loosely in grooves or notches of one or both end flanges. These springs w are normally bowed outwardly as indicated in Fig. 55 3, so that when the core is put into the hollow spool A, as seen in Fig. 1, the springs straightening out will bind against the inner walls of the tube A and frictionally hold the core in place in the spool.

This core C carries at its opposite ends 60 journals j, to permit the spool to be mounted in bearings horizontally in winding.

To illustrate the purpose, use and advantage of my improvement, I will cite by way 65 of example its use in the manufacture of rayon thread or yarn. The spool is first mounted as shown in Figs. 1 and 2, with the expansible core in place in the tubular part of the spool, which is then mounted by the 70 journals j of the core part, horizontally, in suitable bearings in the twisting and winding machine, and the yarn or thread is twisted and wound on the spool on a twisting frame. Then the spool with the thread or yarn on 75 it is subjected to a steaming process to set the twist. Thereafter the spool has to be set vertically on a spindle or other support as indicated by dotted lines in Fig. 5 to draw the thread or yarn off it onto suitable cops, 80 bobbins, etc., or in knitting.

In the handling of these spools, particularly in the steaming operation and afterwards, they are apt to be subjected to more or less rough treatment, with the result commonly that the edges of the flanges become nicked, dented and roughened, and consequently in drawing the yarn or thread off the spools over these nicked and roughened edges, the yarn or thread will catch and be damaged or broken.

It is to meet this difficulty that I mount one of the flanges of the spool upon the core and the other upon the tubular body, so that when the frictional core with its journals is 95 removed, it may be replaced by a substitute flange D, Fig. 4, with a short core d. This substitute flange not being subjected to any rough usage, its flange will remain smooth, so that when the spool is mounted vertically, 100

in any machine in which the yarn or thread is to be drawn off over the edge of this smooth flange, the yarn or thread will not be broken or damaged. This substitute flange D may be of wood, metal or composition of wood or composition of metal. It may be advisable to load it with lead, as indicated at d' in Fig. 4, to give it sufficient weight.

I claim as my invention:

- 10 1. A spool for yarn or thread, consisting of two parts, one a tubular part carrying a winding retaining flange at one end in combination with a removable core to fit therein, said core having a corresponding flange at the other end, journals at both ends, and yielding means retaining said core in place.
- 15 2. A spool for yarn or thread, consisting of two parts, one a tubular part carrying a winding retaining flange at one end in combination with a removable frictional core to fit therein, said core having a corresponding flange at the other end, journals at both ends, and yielding means retaining said core in position.
- 20 3. A spool for yarn or thread, consisting of a tubular body with a winding retaining flange at one end in combination with a removable core having journals at both ends, a corresponding flange at one end and spaced yielding means for retaining said core in position, the tubular body being adapted to receive a substitute short core with flange on removal of the journaled core.
- 25 4. A spool for yarn or thread comprising a tubular body having a winding retaining flange at one end and a removable core having journals at each end thereof and a corresponding flange at one end thereof, annular flanges spaced along the length of said core and fitting said body and resilient means extending between said annular flanges for retaining said core in said body.
- 30 5. A spool for yarn or thread comprising a tubular body having a winding retaining flange at one end and a removable core having a spindle provided with journals at each end and a yarn retaining flange at one end, spaced flanges on said spindle fitting within said body and yielding means carried by said spaced flanges for retaining said core in said body.

In testimony whereof I have signed my name to this specification.

HENRY JOHNSON.
